UNITED STATES PATENT OFFICE.

THOMAS B. FERGUSON, OF ST. LOUIS, MISSOURI.

OIL BURNER.

Application filed April 13, 1925. Serial No. 22,540.

This invention relates to improvements in an oil burner of a type adaptable for use in furnaces, and so arranged as to be readily and conveniently inserted in any style of fire box of a standard heating furnace now on the market.

One of the objects of my invention is to construct a burner, its parts so positioned as to form several air passages for directing the air against the flame and mix therewith in order to obtain a perfect combustion and secure the proper degree of heat by consuming all particles of combustible material and dispensing with carbon which is common in the ordinary oil burners.

Another object of my invention is to construct a burner consisting of a base section, a supporting ring connected thereto and to which are attached standards for supporting the burner in a furnace, a burner pan provided with a plurality of vertical air ducts, and a centrally located frusto conical extension with an opening in its apex, a fuel spreader placed in the pan and separated from the pan forming an air passage, a manifold set over the ducts of the pan for directing air through a central air discharge opening over the spreader, a manifold cover placed over the manifold and so constructed as to form an air passage between the cover and outer surface of the manifold for directing superheated air through a centrally located pipe carried by the manifold and directing the air immediately over the fuel inlet orifice, and a lever mechanism connected to the fuel feed pipe by which the spreader may be shifted horizontally to equalize the space between the pan and spreader.

In conjunction with the parts above described I equip the burner with a flame shield for saddling the flame and directing it to the outer periphery of the burner and a flame deflector all around the burner for deflecting the flame against the sides of the fire box.

By the arrangement of the various air ducts and passages the air is directed in such manner and mixed with the gaseous vapor to produce a proper flammable mixture consuming all particles of combustible material producing an intense heat clean from carbon.

The arrangement of the manifold is such that the air is admitted from the bottom of the burner and discharged evenly over the spreader, and in addition thereto air is also directed from the top of the manifold down to and immediately over the inlet pipe through which the fuel is admitted to the spreader, this air is superheated by the heated manifold as the air passes between the outer surface of said manifold and the inner surface of the manifold covering.

Again by the use of the winged spreader the air passing between the bottom of the pan and spreader causes the flame to consume all particles of combustible material and direct the flame toward the periphery of the burner.

Referring to the drawings,

100

Figure 14, is a detail perspective view of one of the legs or standards made use of by which the assembled burner is supported in the fire box of a furnace.

Figure 15, is a detail perspective view of one of the flame shields for saddling the flame in the pan.

In the general construction of my invention I provide a base portion 20 having a bottom flange 21 which has projecting ears 22 and by which the base is securely attached to a supporting ring 23 by means of bolts 24 or the like.

10 The flange 21 is also provided with cut out portions 25 in which are seated the top portions of the legs or standards 26 connected to the supporting ring 23 by bolts or the like.

15 The top of the base portion 20 has an inwardly extending flange 27 the upper surface provided with a double bead or circular boss 28 forming a supporting recess 29 for the reception of the bottom edge of the 20 burner pan 30.

The burner pan consists of a cylindrical casing 31 provided with a bottom 32, the center portion of the bottom formed into a 25 conical projection 33 having in its apex an opening 34 through which air may pass and also permit the feed pipe 35 to be properly centered relative to the burner.

The pan is also provided with air ducts 36 formed by the casing 37, and each casing is 20 provided with a flange 38 for the support of the manifold.

In the conical portion of the pan is a depressed portion 39 in which is seated an overflow pipe 40 which will drain off any 25 and all superfluous oil from the pan.

In the pan I place a spreader 41 comprising a conical center portion 42 its upper surface provided with grooves 43 for the reception of the fuel, and these grooves are 40 connected by cross grooves 44 to permit the fuel to pass from one groove to the other. Integral with the conical portion are wings 45 consisting of a horizontal portion 46, vertical walls 47 and a projecting flange 48, 45 these wings are arranged to fit between the casings 37 of the pan and are somewhat smaller so that they can be slightly shifted in position for equal adjustment.

On the bottom of the horizontal portions 50 46 of the wings I place ribs 49 which rest on the bottom of the pan and space the spreader so as to form an air passage 50 between the spreader and pan, and the air as it circulates from the bottom through the 55 opening 34 follows the passage between the spreader and pan and up through the passage 51 between the walls of the two and out at the edge 52 thus mixing with the flame as it passes over the edge of the burner.

50 In the apex of the conical portion of the spreader is an opening 53 in which is inserted the fuel inlet pipe 35 and by which the fuel is fed to the burner from the source of supply.

55 The pipe 35 is provided with a collar 54

connected to an arm or lever 55, one end of the lever having an elongated slot 56 at which point the lever is attached to the bottom of the base portion 20, and by means of the lever the pipe together with the spreader 70 to which it is attached may be slidably shifted in either direction horizontally so as to bring the spreader in proper relation with the interior of the pan, thus regulating the flame to spread equally from all sides of the 75 burner.

On top of the ducts 36 of the pan I place a manifold 57 which in this instance consists preferably of three branches each leading to a center discharge opening 58 and which extends downwardly to a reasonable distance above the spreader. The air passing up from the base through the ducts 36 through the branches and down through the discharge opening directly over the flame on 85 the spreader cone.

The upper surface of the manifold is provided with ribs 59, and in the center of the manifold is an opening 60 in which is seated a pipe 61 acting as an air duct for directing air of superheated nature directly over the fuel feed orifice to provide a proper mixture to the fuel.

On the top of the manifold I place a cover 62 which fits snugly over the outer surface of the manifold and by means of the ribs 59 is separated forming an air space 63 for directing the air to the pipe 61. The bottom bulged ends 64 of the cover being so shaped as to fit into the flanged sections 65 of the base portion and covering the air ports 66 and which completes the passage 63 from the bottom of the burner.

These bottom ends 64 may be formed integral with the cover or separate and divided on the line (x) shown in Figure 12, this is to prevent the warping of the material.

When the fuel is fed to the burner and ignited it intermingles or mixes with the air, first by the air admitted from the bottom through the manifold and directed centrally over the spreader, also by superheated air admitted from the bottom over the manifold and directed against the fuel inlet, and the flame is properly spread by the air current passing between the burner pan and spreader discharging at the upper edge shaping the flame into a flaring fashion.

The flame as it is directed outwardly is prevented from shooting upwardly by the flame shields 67 seated on each wing of the spreader, these shields act as a housing and direct the flame over the upper outer edge of the wings, and in order to further deflect the flame outwardly, I place on the burner base a flame deflector 68 which runs all around the burner and is supported on suitable supports 69.

This deflector is set on an angle as shown 120 to direct the flame as near as possible to the

walls of the fire box thus preventing the flame from passing directly upwardly from the pan.

The direction and position of the flame is clearly illustrated in Figure 2.

Having fully described my invention what I claim is.

1. An oil burner comprising a supporting base, a burner pan located thereon, said pan having an integral centrally located frusto conical extension, a spreader located in the pan and separated therefrom forming an air passage between the pan and spreader, said spreader having wings for directing the air to the upper edge of the pan, a manifold supported on the pan, and a manifold covering placed over the manifold forming an air passage between the outer surface of said manifold and the covering, directing the air to a central discharge above and over the frusto conical extension.

2. An oil burner of the character described comprising a base section, a rim to which the same is connected, standards for supporting the same, a burner pan detachably mounted on the base, a plurality of extensions formed on the pan, the bottom of said pan having a central frusto conical extension, a winged spreader located in the pan, said spreader having lugs for separating the spreader from the bottom of the pan forming an air passage, a fuel supply pipe connected to the spreader, a lever mechanism connected to the pipe whereby the spreader may be shifted for regulating the spread of the flame, a manifold placed on the pan, and a manifold cover placed over the manifold, substantially as specified.

3. An oil burner comprising a base, a burner pan positioned thereon, a winged spreader positioned in the pan, a manifold supported on the pan, a manifold cover placed over the manifold, all of said parts when assembled forming various air passages, one passage between the pan and spreader terminating at the upper outer edge of the pan, one passage through the manifold directing air from the bottom to a central

discharge above the spreader, and one passage between the manifold and manifold cover directing an air current from the bottom to a central discharge above the fuel inlet, all directing the air in such manner as to mix with the particles of combustible material creating a sootless flame.

4. A burner of the character described comprising a base with a central opening at its top, a burner pan located on the top of said base, said pan having vertical hollow extensions which act as air ducts, a centrally located frusto conical extension with an opening in its apex forming part of the bottom of the pan, a grooved conical shaped spreader located above the pan's bottom, wings radiating from the center and forming a part of said spreader and arranged to form an air passage between the pan and spreader, a fuel supply pipe leading upwardly and connected to the spreader, a manifold positioned on the hollow extensions of the pan, said manifold directing the air to a central discharge opening above the spreader, a pipe positioned in the manifold's discharge opening forming an air passage from the outside of the manifold for directing heated air directly against the fuel supply, and a manifold cover located over the manifold forming an air passage between the cover and manifold having an inlet at the bottom, and a central outlet above the fuel supply, substantially as specified.

5. A burner of the character described comprising a base, a burner pan located thereon, a winged spreader located in the pan, flame shields positioned on the spreader directing the flame laterally, a flame spreader positioned at the periphery of the burner pan for deflecting the flame against the wall of the fire box, and a covered manifold above the burner for directing air from the bottom to a central outlet positioned above the spreader, substantially as specified.

In witness whereof I hereunto set my hand.

THOMAS B. FERGUSON.
